HYDRAULIC BLENDING MACHINE

Robert C. Hopkins, Alliance, Ohio

Application February 9, 1940, Serial No. 318,085

3 Claims. (Cl. 83—6)

The invention relates to machines for blending oil, gasoline and other liquids and viscous materials which may be mixed and blended, and more particularly to a hydraulic blending machine comprising a rotary attrition mill and a hydraulic impulse turbine or wheel directly connected thereto, so that the liquids to be blended may be admitted under pressure to the machine to rotate the turbine and drive the mill, whereby the liquid is given a preliminary mixing as it passes through the turbine and is further mixed and blended as it is passed through the mill.

The machine may include a rotary cutting, mixing and attrition mill of the general type shown in my prior Patents No. 1,764,020 dated July 17, 1930; No. 1,775,721 dated September 16, 1930; No. 1,796,104 dated March 10, 1931; No. 1,873,409 dated August 23, 1932; or No. 2,111,364 dated March 15, 1938, comprising generally, a rotary cutting, mixing and attrition member associated with a plurality of attrition chambers, an impulse turbine or wheel being fixed upon the shaft of said rotary member located within a housing communicating axially with the attrition mill.

An object of the invention is to provide a housing totally enclosing all of the operating mechanism of the blending machine with all bearings entirely enclosed so as to prevent any leakage of the liquids passing through the machine, whereby explosive liquids such as benzine, gasoline and the like may be safely processed in the machine.

Another object is to provide a hydraulic blending machine comprising a self-contained attrition mill and directly connected turbine for driving the mill by pressure of the liquid being blended.

A still further object is the provision of a combined turbine and attrition mill through which the liquid is passed in order, whereby the liquid is given a preliminary mixing in the turbine and is then further mixed and blended in the mill.

A further object is to provide a blending machine in which the speed of the mill is controlled by the pressure of the inflowing liquid.

The above objects together with others which will be apparent from the drawing and following description, or which may be later referred to, may be attained by constructing the improved hydraulic blending machine in the manner illustrated in the accompanying drawing in which

Figure 1 is a longitudinal sectional view through a hydraulic blending machine constructed in accordance with the invention;

Fig. 2, a transverse section through the turbine, taken as on the line 2—2, Figure 1; and

Fig. 3, a transverse section through the mill, taken as on the line 3—3, Fig. 1.

Similar numerals refer to similar parts throughout the several views.

The mill is enclosed within a housing generally indicated at 10, preferably of cylindric shape and located in horizontal position.

10 A cap or head 11 is connected to one end of the housing 10 as by bolts 12 and is provided with an entirely enclosed bearing portion 13 within which is located a bearing or bushing of any well-known type as shown at 14, within which the journal portion 15 of the adjacent end of the shaft 16 may be journaled.

The other end of the housing 10 is closed by the head or cap 17 connected to the housing 10 as by bolts 18 and so shaped as to form a housing for the turbine which will be later described.

20 A bearing portion 19 is formed in the head 17 and the journal portion 20 of the shaft 16 is journaled therein.

A rotary cutting unit is carried upon the shaft 25 16 which may be in the form of a plurality of disk saws. For this purpose a hub 21 may be fixed upon the shaft 16 as by the key 22.

25 A collar 23 is formed or fixed upon the shaft 16 adjacent to the journal 20 to engage the adjacent end of the hub 21 in order to position the same relative to the shaft.

An annular flange 24 is formed upon the adjacent end of the hub.

30 A plurality of disk saws 25 is mounted upon the hub 21 and extends from the flange 24 to a point near the other end of the hub, at which point a ring flange 26 may be located around the hub and clamped against the adjacent end of the gang of disk saws as by a nut 27 threaded upon the adjacent end portion of the hub, thus, clamping the gang of saws tightly between the flange 24 and the ring flange 26.

35 A jam nut 28 may be located upon the threaded portion 29 of the shaft, a washer 30 being interposed between said jam nut and the nut 27 upon the hub, for locking the nut 27 in adjusted position.

40 A washer 31 may be located around the journal portion 15 of the shaft between the cap 11 and the nut 28 for taking the end-thrust of the shaft in this direction.

45 A plurality of attrition chambers 32 may be formed within the housing 10 by means of longitudinal partition walls 33 and transverse partition walls 34 extending inward from the housing

to a point closely adjacent the periphery of the gang of saws 25.

An impulse wheel 35 is fixed upon the reduced portion 20 of the shaft within the turbine housing 17 and a partition wall 36 is located between the impulse wheel and the rotary cutting unit above described, dividing the turbine from the mill, the central opening 37 in said partition wall forming the only communication between the two housings.

An inlet neck 38 communicates with the turbine housing for the purpose of admitting fluid under pressure from any suitable source, and an outlet pipe 39 leads from the opposite end of the mill housing 10 to any suitable storage receptacle.

In the operation of the improved blending machine, oil, gasoline, or other liquid or viscous material is admitted under pressure through the inlet 38 driving the turbine and through it the directly connected rotary unit in the mill.

The liquid is given a preliminary mixing as it passes through the turbine and is then discharged through the central opening 37 into the mill housing 10 passing around the periphery of the flange 24 and into the attrition chambers 32.

The liquid is given a violent agitation within each chamber by means of rotating the gang of disk saws, being thoroughly mixed and blended as it passes from one chamber to the next until it is finally discharged through the outlet pipe 39.

It will be seen that the combined turbine and mill forms a wholly enclosed structure having no shafts projecting through packing glands or the like, thus, preventing any dangerous leakage of inflammable material passing through the machine.

The liquid will be delivered to the inlet 38 by means of a pump or other pressure medium and by raising or lowering the pressure of the same the speed of the machine may be controlled.

I claim:

1. A hydraulic blending machine comprising a horizontally disposed, substantially cylindric housing, a cap entirely enclosing one end of the housing and shaped to form a turbine chamber, a partition wall between the turbine chamber and the adjacent end of the housing, a cap entirely enclosing the other end of the housing, a concentric bearing socket in each cap, said sockets being open only to the interior of the housing, a shaft located longitudinally through the housing and journaled at its ends in said bearing sockets, a plurality of disc saws fixed upon the shaft in the main portion of the housing, a turbine wheel fixed upon the shaft within the turbine chamber and comprising a plurality of radial vanes having their outer ends curved in the direction of rotation of the turbine wheel, a single, tangential liquid inlet communicating with the turbine chamber, there being a central opening in the partition wall of greater diameter than the shaft forming the only communication

between the turbine chamber and the interior of the main portion of the housing, and a liquid outlet at the other end of the housing.

5 2. A hydraulic blending machine comprising a horizontally disposed, substantially cylindric housing, a cap entirely enclosing one end of the housing and shaped to form a turbine chamber, a partition wall between the turbine chamber and the adjacent end of the housing, a cap entirely enclosing the other end of the housing, a concentric bearing socket in each cap, said sockets being open only to the interior of the housing, a shaft located longitudinally through the housing and journaled at its ends in said bearing sockets, a plurality of disc saws fixed upon the shaft in the main portion of the housing, a series of longitudinal partitions upon the interior of the housing extending inwardly to points closely adjacent to the disc saws and dividing the housing into a plurality of attrition chambers, a turbine wheel fixed upon the shaft within the turbine chamber and comprising a plurality of radial vanes having their outer ends curved in the direction of rotation of the turbine wheel, a single, tangential liquid inlet communicating with the turbine chamber, there being a central opening in the partition wall of greater diameter than the shaft forming the only communication between the turbine chamber and the interior of the main portion of the housing, and a liquid outlet at the other end of the housing.

20 3. A hydraulic blending machine comprising a horizontally disposed, substantially cylindric housing, a cap entirely enclosing one end of the housing and shaped to form a turbine chamber, a partition wall between the turbine chamber and the adjacent end of the housing, a cap entirely enclosing the other end of the housing, a concentric bearing socket in each cap, said sockets being open only to the interior of the housing, a shaft located longitudinally through the housing and journaled at its ends in said bearing sockets, a plurality of disc saws fixed upon the shaft in the main portion of the housing, a series of longitudinal partitions and a series of transverse partitions upon the interior of the housing extending to points closely adjacent to the disc saws and dividing the housing into a plurality of attrition chambers, a turbine wheel fixed upon the shaft within the turbine chamber and comprising a plurality of radial vanes having their outer ends curved in the direction of rotation of the turbine wheel, a single, tangential liquid inlet communicating with the turbine chamber, there being a central opening in the partition wall of greater diameter than the shaft forming the only communication between the turbine chamber and the interior of the main portion of the housing, and a liquid outlet at the other end of the housing.

ROBERT C. HOPKINS.
